ILLUMINABLE HOUSE NUMBER HOLDER OR
SIMILAR ARTICLE

Joseph W. Rackle, Detroit, Mich., assignor of one-half to Glen L. Arnold and one-half to Charles H. Beasley, both of Detroit, Mich.

Application February 3, 1948, Serial No. 144,241

Term of patent 3½ years

(Cl. D1—12)

To all whom it may concern:

Et it known that I, Joseph W. Rackle, a citizen of the United States, residing at Detroit, in the county of Wayne and State of Michigan, have invented a new, original, and ornamental Design for an Illuminable House Number Holder or Similar Article, of which the following is a specification, reference being had to the accompanying drawing, forming part thereof.

Fig. 1 is a perspective view showing the front side and an end of an illuminable house number holder or similar article, embodying my new design.

Fig. 2 is a front elevation thereof, and

Fig. 3 is a sectional view taken substantially along the lines 3—3 in Fig. 2, showing a cross section thereof.

The dominant features of my design reside in the portions shown in full lines.

I claim:

The ornamental design for an illuminable house number holder or similar article, substantially as shown and described.

JOSEPH W. RACKLE.
